United States Patent Office

Des. 187,812
Patented May 3, 1960

187,812

BRACELET OR THE LIKE

Horace Randall, Pawtucket, R.I., assignor to The H.M.H.
Co., a corporation of South Dakota

Application January 9, 1959, Serial No. 54,122

Term of patent 14 years

(Cl. D45—4)

FIG. 1

FIG. 2

FIG. 3

Fig. 1 is a top view of a bracelet or the like showing my new design;

Fig. 2 is a side view thereof; and

Fig. 3 is a perspective view of one link of the bracelet or the like.

The dominant features of my design are shown in full lines.

I claim:

The ornamental design for a bracelet or the like, substantially as shown and described.
